US0D1083940S

(12) **United States Design Patent** (10) **Patent No.:** **US D1,083,940 S**
(45) **Date of Patent:** **** Jul. 15, 2025**

(54) **STAND FOR PORTABLE ELECTRONIC DEVICE**

(71) Applicant: **Pioneer Square Brands, Inc.**, High Point, NC (US)

(72) Inventor: **William Miles Haskins**, Kernersville, NC (US)

(73) Assignee: **Pioneer Square Brands, Inc.**, High Point, NC (US)

(**) Term: **15 Years**

(21) Appl. No.: **29/992,996**

(22) Filed: **Mar. 12, 2025**

(51) **LOC (15) Cl.** **14-06**

(52) **U.S. Cl.**

USPC **D14/447**

(58) **Field of Classification Search**

USPC D14/447, 251, 252, 253, 440, 451, 452, D14/448, 449, 450, 217, 356, 432, 434, D14/439, 250; D13/107, 179; D21/332, D21/333, 324, 326; D6/601; D18/4.4, D18/4.6

(57) **CLAIM**

The ornamental design for a stand for portable electronic device as shown and described.

DESCRIPTION

FIG. 1 is a front perspective view of stand for portable electronic device showing my new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left elevational view thereof.

FIG. 7 is a right elevational view thereof; and,

FIG. 8 is a rear perspective view thereof.

The broken lines in the drawing figures depict portions of the stand for portable electronic device that form no part of the claimed design.

1 Claim, 8 Drawing Sheets
